UNITED STATES PATENT OFFICE.

HAROLD BINNEY, OF NEW YORK, N. Y., ASSIGNOR TO NEALON COMPANY,
A CORPORATION OF NEW YORK.

HOSE-SUPPORTER CLASP.

No. 834,044.

Specification of Letters Patent.

Patented Oct. 23, 1906.

Application filed November 30, 1904. Serial No. 234,907.

To all whom it may concern.

Be it known that I, HAROLD BINNEY, of 10 Lexington avenue, New York city, New York, have invented certain new and useful 5 Improvements in Hose-Supporter Clasps, of which the following is a specification.

The invention relates primarily to the class of the type having a loop and button the shank of which is adapted to be embraced by a portion of the loop to secure the fabric between the button and the loop. Examples of such construction are found in the Gorton patent, No. 552,470, of December 31, 1895, and in the patent granted to 15 Nealon and Binney, No. 603,430, May 3, 1898.

The object of the invention is to simplify the construction of the metallic portions and reduce the number of parts forming the loop 20 and the attachment for the cords or webbing by which the fastener is suspended.

The nature of the invention will be readily understood from the drawings, wherein—

Figure 1 shows one preferred embodiment 25 of the invention. Fig. 2 is the blank for the single metallic part. Fig. 3 is a rear view of the metallic and rubber portions of the clasp. Fig. 4 is a front view of the rubber button and back-plate. Fig. 5 is a central 30 longitudinal section of Fig. 4. Fig. 6 shows one way of preparing the ends of the cord for attachment to the clasp, and Fig. 7 shows a modification of Fig. 5.

So far as the details of the button are concerned, these form the subject-matter of my 35 separate patent application of even date herewith, which application has since received Serial No. 234,906.

Heretofore considerable difficulty has been 40 experienced in combining at once an advantageous operation with a low cost of manufacture of the metallic parts of such fasteners, and several patents have been taken out for various combinations of one, two, three, 45 or more metallic elements in such fasteners. The present invention aims at the difficult accomplishment of combining a great increase in simplicity and low cost of manufacture, with added efficiency and desirability 50 in use. These objects instead of being inconsistent are now both accomplished by the present invention, as follows:

The leg-band B and cord D are not essentials of the invention, though preferably

when the clasp is applied to men's garters the 55 cord D should be elastic and the leg-band B relatively or substantially non-elastic, as patented in the said patent to Nealon and Binney.

C is the metallic loop, formed from a blank 60 having ears C' for securing the back-plate or button-plate to the loop and wings or ears C'' for securing the cord D or other fabric to the clasp. The cooperating button-plate G is preferably of soft rubber backed by a non- 65 resilient fabric G', as well understood, and is preferably corrugated horizontally in front, as shown in Fig. 4, so as to increase its flexibility. Preferably, also, its upper end is thickened and provided with recesses or 70 holes, as shown, for receiving the bent-over ends of the tongue C' when the back-plate is finally secured, as in Fig. 3. The middle perforation may also receive projecting tongues from the two wings C'' when these 75 are bent over, as shown in Fig. 3. The cords or webbing of the garter or other article, to which the clasp is to be affixed is secured by clamping down the wings C'', as shown in Fig. 3. In men's garters the two 80 ends of the cord D may preferably be tied in a knot (see Fig. 6) and laid within and clamped and embraced by the wings C'', or the two ends of the cord may, if desired, be first secured together in any well-known 85 manner and the head or terminal so formed laid in and secured by the wings C''. In any event and however the cord or webbing be secured by the wings C'' it will be seen that the metal of the loop serves the double function of rigidly securing it to both the back- 90 plate and the cord or other webbing or fabric.

The present clasp consists in its simplest form entirely of two parts, exclusive only of 95 the fabric or cord to which it is fixed. These two parts are the loop member and the single button and back-plate, this combination being the same, however, whether the button is an all-rubber button or is internally reinforced, as set forth in my above-named application of even date herewith.

The invention eliminates the well-known hinged connection between the loop member and the back-plate, doing away entirely with 105 at least one element of such old device. So, also, in providing the normally parallel loop and back-plate without any joint between

them it facilitates the putting on and taking off of the clasp, because the tip of the finger suffices to open the clasp by flexing the back-plate G, while the loop will be held stiff, even if held by its extreme upper ends, where the wings C' are folded over.

What I claim, and desire to secure by Letters Patent, is as follows:

1. In a clasp of the type having a button or embraced member and an external loop or embracing member which embraces the button, the button member comprising essentially an integral button and back-plate and a loop member rigidly secured to the back-plate and having bent-over portions adapted to embrace the cord or fabric to which the clasp is fixed.
2. In a clasp of the type having a button or embraced member and an external loop or embracing member which embraces the button, the button and back-plate comprising an integral mass of material such as soft rubber and a loop member against the upper portion of which the upper end of the said button member lies and is fixed so as to lie substantially parallel therewith when not flexed.
3. In a clasp of the type having a button or embraced member and an external loop or embracing member which partially embraces the button, a loop member and a combined button and back-plate, said back-plate having a portion at its upper end thickened on the side toward the loop and secured rigidly to the loop at the said thickened portion.
4. A clasp comprising a back-plate, a button, and a button-engaging loop having means for rigidly engaging said back-plate and means for engaging a supporting fabric.
5. A clasp comprising an integral back-plate and button, and a button-engaging

loop having means for rigidly engaging said back-plate and means for engaging a supporting fabric.

6. A clasp comprising an integral back-plate and button having a thickened portion at the upper end of the plate, and a button-engaging loop having means for rigidly engaging said back-plate and means for engaging a supporting fabric.

7. A garment-supporter clasp comprising a rigid loop, an integral button and flexible back-plate, and means engaging the upper end of said back-plate for securing said back-plate rigidly to said loop.

8. A garment-supporter clasp comprising a rigid loop, an integral button and flexible back-plate, and means integral with said loop engaging the upper end of said back-plate for securing said back-plate rigidly to said loop.

9. A garment-supporter clasp comprising an integral button and flexible back-plate, and a metal loop formed with lugs at its upper end engaging with the back-plate for rigidly retaining the latter in operative position.

10. A garment-supporter clasp comprising an integral button and flexible back-plate provided with apertures, and a metal loop formed with lugs at its upper end engaging into said apertures in the back-plate for retaining it in operative position.

In testimony whereof I have signed this specification in the presence of two subscribing witnesses.

HAROLD BINNEY.
